FLUID ENGINE

Carl Wilhelm Henrik Dücker Bennet and Anders
Johan Emil Rylander, Stockholm, Sweden, as-
signors to Louise Gunnilla Violet Bennet, Rune-
borg, Stocksund, Sweden

Application October 14, 1940, Serial No. 361,174
In Sweden October 13, 1939

7 Claims. (CL. 103—149)

(Granted under the provisions of sec. 14, act of
March 2, 1927; 357 O. G. 5)

Our invention relates to engines, such as pumps, compressors or motors for liquid or gaseous working fluid of the type comprising a casing, a flexible wall in said casing arranged to perform uni-directional wave-like movements, and a movable member adapted to actuate said flexible wall or to be actuated thereby. The construction and mode of operation of an engine of the type referred to will be briefly described with reference to Figs. 1 and 2 of the accompanying drawings, in which Fig. 1 is a plan view of an engine of the type referred to, the cover thereof being removed, and Fig. 2 is a section on the line II—II, Fig. 1.

The engine comprises an oblong casing having a rectangular cross-section and being provided with a cover 11. At the ends of the casing there are provided bearings 12 and 13 for a helically shaped rod 14 hereinbelow termed the helix which forms the above-named movable member. A flexible band 15 and 16, respectively, is disposed on either side of the helix 14, said bands being connected to the bearings 12 and 13 and constituting flexible displaceable walls actuated by the helix 14. The bands extend throughout the entire height of the casing as viewed in Fig. 2 so as to engage the cover 11 and the bottom wall of the casing with a tight fit. The distance between the ends of the bands is so much less than the actual length of the bands that they are in contact with the helix throughout the length of the same. The casing is provided with connections 17, 18, 19, 20 which communicate with the interior of the casing and serve as inlets and outlets for the working fluid.

If rotational movement is imparted to the helix 14, the bands will perform uni-directional wave-like movements, each band acting as an endless piston having a continuous uni-directional movement. In this instance, the apparatus works as a displacement pump propelling a constant quantity of liquid for each revolution of the helix. The working chambers 21 and 22 confined by the walls of the casing and the bands will thus be moved in the direction from the inlets 17, 18 to the outlets 19 and 20, respectively, and the liquid enclosed in said chambers will be propelled in the said direction. The apparatus may also be operated as a motor in which case a fluid under pressure is supplied to the casing, which fluid due to its pressure upon the bands imparts rotational movement to the helix from which power can be derived.

The present invention has for its principal objects to improve and simplify the construction shown, to prevent the bands from occupying an

inclined position and from coming out of contact with the walls of the casing, and to provide a band construction including a plurality of individual elements designed to prevent leakage between adjacent working chambers. The invention is an improvement over the subject matter embodied in the Bennet Patent No. 2,244,418, dated July 23, 1941.

These and other objects are attained by mechanism illustrated in Figs. 3 to 14, in which—

Fig. 3 shows a portion of the novel band construction with appertaining helix, viewed in the same direction as Fig. 1;

Fig. 4 is a side elevation of the elements shown in Fig. 3;

Fig. 5 is a section to an enlarged scale of one of the elements of the bands, the section being taken on the line V—V, Fig. 6;

Fig. 6 is a plan view of the element;

Fig. 7 is a modification of an element;

Figs. 8 and 9 illustrate an embodiment in which the bands are surrounded by a flexible cover;

Fig. 10 is a further modification;

Fig. 11 is a plan view of the modification shown in Fig. 10;

Fig. 12 is a section on the line XII—XII, Fig. 10;

Fig. 13 is a plan view of a still further modification;

Fig. 14 is a section taken on the line XIV—XIV, Fig. 13.

In accordance with the present invention, the flexible bands or walls 15 and 16 shown in Figs. 1 and 2 are replaced by a number of contiguous elements. With reference to Figs. 5 and 6, it will be seen that each element 30 is in the form of a substantially rectangular body of crescent-shaped cross-section. Each element has an oblong opening 31 for the helix 14. As will be seen from Fig. 5, the element is bounded on the front side as well as on the rear side by cylindrical surfaces 32 and 33 respectively having the same radius of curvature r , whereas the upper side 34 and the lower side 35 are plane. The width of the opening 31 corresponds substantially to the diameter of the rod forming the helix 14, whereas the length of said opening is at least equal to the sum of said diameter and the amplitude of the helix.

Figs. 3 and 4 illustrate how a flexible wall each on either side of the helix 14 is formed by a number of elements 30 being placed adjacent to each other. Due to the fact that the radii of curvature of the surfaces 32 and 33 are equal to each other the elements will be maintained

in mutual sealing contact during the relative movement of the elements caused by the wave-like movement of the walls with the result that an effective seal will be obtained not only at the places where the crests of the walls are in contact with the casing 10, but also between the working chambers located on either side of the helix. The elements forming the walls are preferably disposed in such a manner that the convex surfaces 33 are directed toward that side of the engine where the highest pressure is prevailing; otherwise the pressure of the working fluid exerted on the edges 36, 37 (see Fig. 5) would tend to bring the elements out of contact with each other. The length of the elements, that is the distance between the surfaces 34 and 35 (Fig. 6) should obviously be equal to the height of the working spaces as viewed in Fig. 2 so that the elements can slide in the working spaces with a tight fit on the upper and lower wall of the casing. Due to the fact that the elements engage each other in the manner indicated they are prevented from occupying inclined positions in the casing.

According to different fields of application of the apparatus the elements 39 may consist of metal, Bakelite, impregnated wood or the like. In order to increase the sealing effect between the elements, a sealing strip 38 of suitable material, such as rubber, lead or Celluloid may be inserted in one of the cylindrical surfaces of the elements, as shown in Fig. 5. Such sealing strip extends preferably in a closed path around the opening 31 (Fig. 6).

If the elements consist of a non-metallic or soft material, it can be advantageous to provide surfaces of a suitable hard material at the places where the elements are in contact with each other and with the helix. An arrangement of this kind is shown in Fig. 7 in which the contacting surfaces consist of a metal lining 39.

In the embodiment shown in Figs. 8 and 9, the elements 30 are entirely enclosed by a cover 40 of suitable material, such as rubber or Celluloid, which not only renders possible a perfect seal between the working chambers but also substantially reduces the friction occurring between the flexible walls and the walls of the working chambers if water is used as a working medium and the cover 40 consists of rubber. If, however, metallic contact is desired between the flexible walls and the walls of the casing, a thin wire 41 may be wound about the cover 40, as shown in Figs. 10-12.

Figs. 13 and 14 illustrate an embodiment in which the helix 14 is not in direct contact with the plane sliding faces 42 of the elements 30. In this instance, individual and exchangeable sliding shoes 43 are inserted between the helix and the elements, which shoes should obviously be short as viewed in the longitudinal direction of the helix so as not to interfere with the wave-like movements of the flexible walls.

What we claim is:

1. A fluid engine comprising a casing, a displaceable wall in said casing arranged to perform a uni-directional wave-like movement, and a movable member for cooperation with said displaceable wall, whereby to effect wave-like movement of said wall, said displaceable wall including a series of contiguous elements arranged to reciprocate in said casing and having openings for the reception of said movable member, said movable member being arranged to cooperate with the walls of said opening whereby to impart

individual reciprocating movements to said elements, the abutting faces of said elements being bounded by cylindrical surfaces having equal radii of curvature.

5. 2. A fluid engine comprising a casing, a displaceable wall in said casing arranged to perform a uni-directional wave-like movement, and a movable member for cooperation with said displaceable wall, whereby to effect wave-like movement of said wall, said displaceable wall including a series of contiguous elements arranged to reciprocate in said casing and having openings for the reception of said movable member, said movable member being arranged to cooperate with the walls of said opening whereby to impart individual reciprocating movements to said elements, said elements being substantially crescent-shaped in cross-section.

3. A fluid engine as claimed in claim 1 and further characterized by sealing means provided on said abutting faces, said sealing means extending in a closed path around said opening.

4. A fluid engine as claimed in claim 1 and further characterized by a lining of hard material provided on the surfaces of said elements being in contact with each other and with said movable member.

5. A fluid engine comprising a casing, a flexible wall in said casing arranged to perform a uni-directional wave-like movement, and a movable member for cooperation with said flexible wall, whereby to effect wave-like movement of said wall, said flexible wall including a series of contiguous elements arranged to reciprocate in said casing and having openings for the reception of said movable member, said movable member being arranged to cooperate with the walls of said opening whereby to impart individual reciprocating movements to said elements, said elements being substantially crescent-shaped in cross-section, the convex surfaces of said elements being directed toward the high-pressure end of said engine.

6. A fluid engine comprising a casing, a flexible wall in said casing arranged to perform a uni-directional wave-like movement, and a movable member for cooperation with said flexible wall, whereby to effect wave-like movement of said wall, said flexible wall including a series of contiguous elements arranged to reciprocate in said casing and having openings for the reception of said movable member, said movable member being arranged to cooperate with the walls of said opening whereby to impart individual reciprocating movements to said elements and individual exchangeable sliding shoes disposed between said movable member and said elements.

7. A fluid engine comprising a casing, a displaceable wall in said casing arranged to perform a uni-directional wave-like movement, and a movable member for cooperation with said displaceable wall, whereby to effect wave-like movement of said wall, said displaceable wall including a series of contiguous elements arranged to reciprocate in said casing and having openings for the reception of said movable member, said movable member being arranged to cooperate with the walls of said opening whereby to impart individual reciprocating movements to said elements, the abutting faces of said elements being arranged to permit bending of the wall but preventing twisting movement thereof.

CARL WILHELM HENRIK DÜCKER BENNET,
ANDERS JOHAN EMIL RYLANDER.
